(57) **CLAIM**

The ornamental design for an air intake for a vehicle, as shown and described.

DESCRIPTION

This application is related to the following co-pending application, filed on even date herewith: Application Ser. No. 29/258,852, entitled “Surface Configuration of a Vehicle, Toy, and/or Other Replicas”.

FIG. 1 is a left, front perspective view of an air intake for a vehicle showing our new design, the right, front perspective view being a mirror image thereof;

FIG. 2 is a front view thereof; and,

FIG. 3 is a top view thereof.

The broken lines are for illustrative purposes only and form no part of the claimed design.

1 Claim, 2 Drawing Sheets

FIG. 1

FIG. 2

FIG. 3
